(57) **CLAIM**

We claim the ornamental design for a camera, as shown and described.

DESCRIPTION

FIG. 1 is a top, front, right side isometric view of a camera showing a first embodiment of our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a top, rear, right side isometric view thereof;
FIG. 9 is a front, top, left side isometric view thereof;
FIG. 10 is a bottom, rear, left side isometric view thereof;
FIG. 11 is a top, front, right side isometric view of a camera showing a second embodiment of our new design;
FIG. 12 is a front elevational view thereof;
FIG. 13 is a rear elevational view thereof;
FIG. 14 is a right side elevational view thereof;
FIG. 15 is a left side elevational view thereof;
FIG. 16 is a top plan view thereof;
FIG. 17 is a bottom plan view thereof;
FIG. 18 is a top, rear, right side isometric view thereof;
FIG. 19 is a front, top, left side isometric view thereof; and,
FIG. 20 is a bottom, rear, left side isometric view thereof.
The subject matter shown in broken line depicts portions of the camera in which the design is embodied that form no part of the claimed design.

1 Claim, 14 Drawing Sheets
